Primary Examiner — Janice Hallmark*Assistant Examiner* — Adedoyin Taiwo Odeyale*(74) Attorney, Agent, or Firm* — Kunzler Bean & Adamson, PC; Michael Bartholomew(57) **CLAIM**

The ornamental design for a floating fountain, as shown and described.

DESCRIPTION

FIG. 1 is a front, right and top perspective view of a floating fountain, showing my design.
FIG. 2 is a rear, left and bottom perspective view thereof.
FIG. 3 is a front elevation view thereof.
FIG. 4 is a rear elevation view thereof.
FIG. 5 is a left side elevation view thereof.
FIG. 6 is a right side elevation view thereof.
FIG. 7 is a top plan view thereof.
FIG. 8 is a bottom plan view thereof; and,
FIG. 9 is an enlarged view of detail 9 in FIG. 2.
The broken lines depict portions of the floating fountain that form no part of the claimed design.
